UNITED STATES PATENT OFFICE.

FREDERICK I. MARTIN, OF MELLEN, WISCONSIN.

RELEASABLE STAKE FOR LUMBER-CARS.

1,122,966.

Specification of Letters Patent. Patented Dec. 29, 1914.

Application filed September 14, 1914. Serial No. 861,612.

To all whom it may concern:

Be it known that I, FREDERICK I. MARTIN, a citizen of the United States, residing at Mellen, in the county of Ashland and State 5 of Wisconsin, have invented certain new and useful Improvements in Releasable Stakes for Lumber-Cars; and I do hereby declare the following to be a full, clear, and exact description of the invention, such as 10 will enable others skilled in the art to which it appertains to make and use the same.

This invention has for its object to provide stakes for supporting lumber on railway cars and novel means for reliably securing the stakes in vertical position and permitting the same to be released from the side of the car opposite from that from which the lumber is unloaded.

Another object is the provision of a chain 20 connecting the upper extremities of each pair of stakes and so arranged as to be automatically disengaged when either stake of the pair is released.

With these and other objects in view, the 25 invention consists in the novel construction, arrangement and formation of parts as will be hereinafter specifically described, claimed and illustrated in the accompanying drawings, in which:

30 Figure 1 represents a transverse sectional view, partly broken away, through the body of a lumber car, showing the application thereto of the releasable stakes. Fig. 2 represents a horizontal sectional view on the line 2—2 of Fig. 1. Fig. 3 represents a longitudinal horizontal sectional view on the line 3—3 of Fig. 1. Fig. 4 represents an end elevation, partly broken away. Fig. 5 represents an enlarged transverse sectional 35 view on the line 5—5 of Fig. 2, and Fig. 6 represents a perspective view of two of the clamping blocks detached.

Referring to the drawings in detail, wherein similar reference numerals designate corresponding parts throughout the 45 several views, the numeral 6 indicates fragments of the longitudinal members of the body of a railway lumber or freight car. I-beams 7 are arranged in pairs and secured 50 transversely of the longitudinal members 6 of the car and are secured in spaced relation by straps 8 connecting said I-beams adjacent their free extremities and having recesses 10 in their outer edges. The I-beams 55 7 are spaced sufficient distance apart to snugly receive the lower extremities of

stakes 11, the opposite extremities 12 of which are beveled and adapted to engage the inclined upper faces of laterally projecting lugs 13 carried by the longitudinal 60 members 6 below each pair of I-beams 7. Adjacent their lower extremities the stakes 11 are partially seated within the recesses 10 of the straps 8, and the beveled ends 12 thereof are provided with longitudinal recesses 15 adapted to receive the shanks of eye bolts 16. One end of a chain 17 is secured to the eye bolt 16 of one of each pair of stakes 11, and the opposite end portion of said chain is adjustably secured to the eye 70 bolt 16 carried by the other stake of the pair. The free end of the chain 17 is provided with a clip 18 adapted to be adjustably secured to the links of said chain intermediate its ends.

A pair of clamping blocks 20 are slidably mounted between the web portions of each pair of I-beams 7 at each end of each pair of beams. The inner extremities of the blocks 21 are suitably recessed to receive the 80 lower extremities of the stakes 11 and the top and bottom edges of said blocks are suitably shaped to fit between the upper and lower horizontal flanges of the I-beams 7. The free extremities of a cable 22 are 85 secured in the blocks 20 of each pair and the medial portion of said cable extends inwardly between the I-beams 7 and is connected with a chain 23 extended to a point nearly adjacent the opposite ends of the I- 90 beams 7 and through an aperture formed in the web portion of one of said I-beams.

Plates 24 are slidably mounted over the 95 apertures in the opposite extremities of the I-beams 7 receiving the chains 23 and are each formed with apertures 25 connected by a slot 26 of considerably less width than the diameter of the apertures 25. The apertures 25 are of such width that when registered with the apertures in the I-beams 100 7 the chains 23 may freely pass therethrough, however, when said plates are moved so as to register the slcts 26 with the openings in the I-beams 7 a link of the chain 23 is slipped into the slot 26 and thus 105 locked against further longitudinal movement. The plates 24 are operable at a distance from the car by suitable chains 27 connected with the outer extremities of the plates.

In use, the stakes 11 are reliably secured in vertical operative position, as illustrated

in full lines in Fig. 1, by the clamping blocks 20, which latter are secured by the cables 22, chains 23 and plates 24. The lumber is piled, in the usual manner, upon the I-beams 7 and between the stakes 11. When it is desired to unload the lumber, the chain 23 securing the blocks 20 on the side of the car from which it is desired to drop the lumber is released by sliding the plates 24 so as to register one of the openings 25 with the opening through the web portion of the I-beam 7, thus permitting the chain 23 to slip longitudinally under the pressure exerted upon the lower extremities of the stakes 11 and the blocks 20. When the stakes 11 along one side of the railway car are released, said stakes drop downwardly and outwardly from the side of the car and in their downward movement the shanks of the eye bolts 16 slip out of the recesses 15 in the upper extremities of the stakes 11 and thus permit the load of lumber to be unloaded.

What I claim is:

- 25 1. A device of the character described comprising a pair of beams, means connecting said beams adjacent their opposite extremities, stakes engaged against said connecting means, means for limiting the downward movement of said stakes, and means for securing said stakes against said securing means including pairs of blocks and connections between the blocks of each pair.
- 35 2. A device of the character described comprising a pair of beams, a support for said beams, lugs carried by said supports having downwardly and outwardly inclined upper faces, means connecting said beams adjacent their opposite extremities, stakes

engaged upon the inclined faces of said lugs and against said connecting means, and means for securing said stakes in position including pairs of blocks, and means connecting said blocks.

45

3. A device of the character described comprising a support, a pair of I-beams secured over said support, means connecting said beams adjacent their opposite extremities, a stake engaged against said connecting means, a pair of clamping blocks disposed between said beams and movable against said stakes, a flexible member connecting said blocks, and means at the end of said beam opposite from said blocks for securing said flexible member in adjusted position.

50

4. A device of the character described comprising a support, a pair of I-beams secured upon said support in spaced relation, means connecting said I-beams adjacent their opposite extremities, lugs secured to said supports and having downwardly and outwardly inclined upper faces, stakes engaged upon the inclined faces of said lugs and against said connecting means, pairs of blocks movable against said stakes, flexible means connecting the blocks of each pair and extending through the web portions of said I-beams, means for securing said flexible members in adjusted position, eye bolts positioned in the upper extremities of said stakes, and means adjustably connecting said eye bolts.

65

70

In testimony whereof I affix my signature in presence of two witnesses.

FREDERICK I. MARTIN.
